UNITED STATES PATENT OFFICE

GEORGE FREDERICK FRENCH AND ROGER FRENCH, OF MANCHESTER, ENGLAND

LADDER WEB FOR VENETIAN BLINDS

Application filed August 25, 1930, Serial No. 477,764, and in Great Britain September 14, 1929.

This invention relates to ladder webs for Venetian blinds.

As ordinarily made, such ladder webs comprise two continuous full-width parts called body webs, and two part-width webs lying side by side between the body webs, such part-width webs each being inter-woven at intervals with the body webs, first with one and then the other, so as to be intermittent and form staggered lath "straps" or bridges between the body webs. The laths of the blind rest upon the straps, and cords passing through the laths and between the two sets of intermittent straps prevent endwise movement of the laths.

An objection to Venetian blinds is that if subject to a draught, say when hung at an open window, or outside a window, or if in positions other than the vertical, say over a sloping skylight, the laths are apt to be displaced, and allow light to pass between them, and are also liable to rattle.

To overcome such drawback, it has already been proposed to provide ladder webs with double or two-ply woven straps, the laths passing between the plies, but such tapes have been expensive and slow to manufacture, and have presented difficulties in weaving owing to an increased number of shuttles being needed, necessitating special looms with complicated dobby or jacquard motions.

The object of this invention is to provide a ladder web with double straps which can be woven with the same number of shuttles as the ordinary single strap webs, and at practically the same rate of production, which can be manufactured at a cost very little, if anything at all, above the cost of the ordinary single straps tape, using virtually standard looms, and with little complication in the warp-shedding devices.

According to the invention the improved ladder web is characterized by double straps wherein the second or extra strap is formed from an extra warp or warps left unwoven for a portion or portions of its length. In the preferred example there are a number of warps left entirely free from weft during the weaving of the straps. Ladder webs ac-

cording to this invention may be woven on the same looms used for single strap webs, i. e. having four tiers of shuttles.

In a modification the extra strap of one part-width web may, for a portion of its length, be supplied with weft from the shuttle used to weave the ordinary strap of the other part-width web and vice versa.

In a further modification, the two straps of each pair are supplied alternately with a number of picks of weft, and the "crossings over" from one strap to the other subsequently severed or removed.

The extra or "dummy" straps thus formed, not having to bear the weight of a lath, but merely to lie on the top of the lath, are quite sufficient to prevent displacement of the lath.

The "dummy" straps may be directly above the usual straps or to one side thereof, or even on the other half or side of the body webs, but clear of the woven straps on that side.

The invention will be further described with reference to the accompanying drawings, wherein:—

Figs. 1 and 2 are edge and side views respectively of a ladder web constructed according to one form of the invention.

Fig. 3 is a part sectional perspective view of the web shown in Figs. 1 and 2, illustrating the use of the improved double straps.

Figs. 4 to 7 are diagrammatic views illustrating methods of weaving the improved web, hereinafter described.

Fig. 8 is a view corresponding to Fig. 2, but to a smaller scale, and illustrating a further form of the invention.

As shown in Figs. 1 to 6, the ladder web comprises two full-width woven webs A, B, and two part-width woven webs C, D, the latter being woven into the former at regular intervals. The extra or "dummy" straps in this form of the invention consist of warp threads only, without weft, see Figs. 1 to 3, and may be obtained by introducing a number of extra warp threads *a*, or by selecting some of the warps of the part-width webs where they are not woven into the body webs. During the time that the ordinary straps C and D are being woven, these selected warp

threads do not shed or divide with the ordinary warps *b* and *c* but are held fixed so that no weft is inserted between them, see Figs. 4, 5 and 6. This can conveniently be accomplished by adding additional hooks or jacks on the jacquard or dobby (or by introducing a second jacquard or dobby) and additional heald shafts, for the extra warps. A tape thus produced has a length of unwoven or 10 floating warp threads *a* against each woven strap, thus producing the desired double strap. The laths of the blind lie between the double straps as may be seen from Fig. 3.

In another form of the invention, the extra 15 strap is obtained as in the previously described example, i. e. by means of extra warps *a*, or selected warps, but during the time that the usual strap C or D is being woven into the two body webs (a distance of about $1\frac{1}{2}$ " to 20 $1\frac{3}{8}$ " for a strap of the average length of $2\frac{1}{2}$ ", and represented by the reference *d* in Fig. 8), the shuttle for such strap, which throughout that period is not putting weft into the strap, although crossing the web at 25 each pick, is employed to insert weft in the warps *a* forming the opposite extra strap, as represented by the reference *e* in Fig. 8, the extra warps being separated by the healds to receive the weft. The shuttle for the strap 30 C inserts weft threads in the "dummy" opposite the strap D, and vice versa. This is accomplished by shedding the selected warps by means of extra heald shafts fitted for the purpose. The weft threads will be inserted 35 in the dummy straps for a length equal to the length taken up by the binding of the straps in the body webs. The weft in the "dummy" straps will only connect in the middle of the strap warps *a* but will spread out to a certain 40 extent over the length of such straps.

In a further form of the invention and as illustrated in Fig. 7, the lath straps are woven two-fold or V shape, that is to say, the straps C and *a* or D and *a* are supplied alternately 45 with weft from the same shuttle and the shedding is such that say 6/8 picks of weft are first inserted in the top half, then a similar number in the bottom half, and so on. The two halves are thus joined by a number of "cross- 50 ings" of weft *f* to each strap, which on being cut will produce two tapes. These may be slightly imperfect owing to their each having only half the usual number of picks and those distributed in periodic patches, but the tendency will be for the weft to distribute itself 55 over the whole length of strap warp (especially if a coarse weft is used) producing light tapes.

Whilst preferring the arrangement of extra warps only or part extra warps and part weft to form dummy straps, a length or lengths of narrow braid or tape or cords may be used as part of the warp.

What we claim is:—

65 1. A ladder web for Venetian blinds, hav-

ing double straps one of which is formed by selecting and holding out a number of warps from the other whilst the latter is being woven, as set forth.

2. A ladder web for Venetian blinds, having double straps one of which comprises unwoven warp threads which have not been shedded during the weaving of the other, as set forth.

3. A ladder web for Venetian blinds having two full-width webs and two part-width webs and having double straps according to claim 2, characterized in that the otherwise unwoven warp threads of one part-width web are supplied with weft from the shuttle which normally weaves the straps of the other part-width web, whilst the latter is being woven into the full-width webs, as set forth.

4. A ladder web for Venetian blinds, having double straps, each of which is formed in portions of its length by unwoven warp threads which have not been shedded during the weaving of the opposite parts of the other, as set forth.

In testimony whereof we have signed our names to this specification.

GEORGE FREDERICK FRENCH.
ROGER FRENCH.
